(57) **CLAIM**

The ornamental design for an electronic device, as shown and described.

DESCRIPTION

FIG. 1 is an isometric perspective view of an electronic device with the electronic device in a first configuration, according to an embodiment; and,

FIG. 2 is an isometric perspective view of an electronic device with the electronic device in a second configuration, according to the embodiment.

The broken lines and the unshaded regions bounded by broken lines of the preceding FIGURES illustrate boundaries for the FIGURES; however, the broken lines and the unshaded regions bounded by broken lines form no part of the claimed design. Non-oblique line shading is meant to show contour and not surface ornamentation.
